ATTORNEY

UNITED STATES PATENT OFFICE.

FREDERICK BAYER, OF JACKSONVILLE, FLORIDA.

PENCIL HOLDER.

Application filed February 21, 1922. Serial No. 538,301.

To all whom it may concern:

Be it known that I, FREDERICK BAYER, a citizen of the United States, residing at Jacksonville, in the county of Duval and

5 State of Florida, have invented new and useful Improvements in Pencil Holders, of which the following is a specification.

This invention relates to a pencil holder, the object of the invention being to pro-

10 vide a pair of jaws for holding a pencil between them with means for attaching the jaws to a garment.

Another object of the invention is to provide a pair of holders with means for connecting them together in order to support 15 two pencils.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side view of the holder.

30 Figure 2 is a view showing a pair of holders connected together,

The remaining figures are detail views.

In these views 1 and 2 indicate the jaw members which are of curved shape in cross 35 section to conform to the shape of the pencil, each jaw member being provided with ears 3, intermediate their ends, which are perforated to receive the rivets 4 which pivotally connect the two members together.

40 The jaw members are tapered, as shown, with the large parts at the upper ends so as to facilitate the placing of a pencil between the holder. As the pencil is forced through the holder its pointed end will 45 strike the small ends of the jaws and thus force them apart. The small ends are flared outwardly, as at 5, and an appreciable distance above said ends enlargements 6 are formed on the jaw members. A band 7 of

50 resilient material is placed around the jaw members between their flared ends and the

enlargements 6. A pin 8 is secured to one of the jaw members and a hook 9 is also secured to said jaw member to receive the free end of the pin.

55 Figure 2 shows a pair of holders A and B, connected together by the cross plates 10 so that two pencils can be held. The pin 8' is connected with the upper plate and the hook 9' with the lower plate.

60 The resilient band will draw the two jaw members together and thus cause them to grip the pencil.

The resilient member may be located at any point below the pivotal point 4 as will be understood.

It is thought from the foregoing description that the advantages and novel features of my invention will be readily apparent.

I desire it to be understood that I may 70 make changes in the construction and in the combination and arrangement of the several parts, provided that such changes fall within the scope of the appended claims.

What I claim is:—

75 1. A pencil holder of the class described comprising a pair of jaw members pivotally connected together, a band of resilient material encircling the jaw members for causing them to grip a pencil and a retaining means for said band.

2. A pencil holder of the class described comprising a pair of jaw members of tapered formation and pivotally connected together, a resilient band encircling the 85 smaller ends of the jaw members and projections on the jaw members forming spaces for receiving the band.

3. A pencil holder of the class described comprising a pair of jaw members of curved 90 shape in cross section and of tapered shape, means for pivotally connecting the central portions of the jaw members together, the small ends of the jaw members flaring outwardly, projections on the outer faces of 95 the jaw members above the flaring ends, a band of resilient material encircling the jaw members between the projections and flaring ends and means on the holder for attaching the same to a garment.

100 In testimony whereof I affix my signature.

FREDERICK BAYER.
